Primary Examiner — Leanne Was-Englehart*(74) Attorney, Agent, or Firm* — Reinhart Boerner Van Deuren P.C.(57) **CLAIM**

I claim the ornamental design for a circle compass, as shown and described.

DESCRIPTION

FIG. 1 is a first top perspective view of the circle compass; FIG. 2 is a second top perspective view of the circle compass;

FIG. 3 is a third top perspective view of the circle compass; FIG. 4 is a bottom perspective view of the circle compass;

FIG. 5 is a front view of the circle compass;

FIG. 6 is a rear view of the circle compass;

FIG. 7 is a side view of the circle compass;

FIG. 8 is a side view of the circle compass showing the side opposite that shown in FIG. 7;

FIG. 9 is a top view of the circle compass; and,

FIG. 10 is a bottom view of the circle compass.

The ornamental design which is claimed is shown in solid lines in the drawings. Broken lines form no part of the claimed design. The dashed lines shown in the drawings illustrate general environmental features.
